Primary Examiner — Mark Goodwin(74) *Attorney, Agent, or Firm* — John L. Crimmins; Audrey Babcock; Aleya Champlin**CLAIM**

We claim the ornamental design for packaging for dough product, as shown and described.

DESCRIPTION

FIG. 1 is a top plan view of a packaging for dough product showing our new design; the extra broken line showing of a packaging for a dough product represents a series of objects and forms no part of the claimed design; and,
FIG. 2 is an end view thereof, all other end views being a mirror image thereof.

The broken line showing of a representative dough product is included for the purpose of illustrating environmental structure only and forms no part of the claimed design.
